UNITED STATES PATENT OFFICE

EMIL J. SEEBER, OF CHICAGO, ILLINOIS

JACK

Application filed January 8, 1932. Serial No. 585,569.

This invention relates to certain novel improvements in jacks, and has for its principal object the provision of an improved construction of this character which will be highly efficient in use and economical in manufacture.

It is the primary object of this invention to provide an improved jack of the character hereinafter described.

10 Other objects will appear hereinafter.

The invention consists in the novel combination and arrangement of parts to be hereinafter described and claimed.

15 The invention will be best understood by reference to the accompanying drawing, showing the preferred form of construction and in which:

Fig. 1 is a top plan view of the jack;

Fig. 2 is a sectional view on line 2—2 in 20 Fig. 1;

Fig. 3 is a side elevational view, on line 3—3 in Fig. 2, with parts broken away;

Fig. 4 is a fragmentary detail view; and

25 Fig. 5 is a sectional view on line 5—5 in Fig. 2.

In the drawing which illustrates a preferred and practical embodiment of the invention, 10 indicates the foot or base of the jack; said foot being attached to the post or standard 11. Movable axially along the jack post or standard 11 is a member 12, and likewise movable axially along the post or standard 11 is a member 13; the member 12 and member 13 being moved axially along the post 11 by means of the hereinafter described mechanism.

30 This mechanism includes an operating lever 14 which is attached to a crank 15 that is journaled in the member 12; said crank having an eccentric throw 16 upon which floats a yoke 38 of a link 17 which has its other end connected to a pin 18 in the member 13.

35 Arranged adjacent a portion 19 of the member 12 is a gripping jaw 20 which is normally urged slightly away from the standard 11 by a spring-urged screw 21 so that the jaw 20 may be moved relative to the standard. Said portion 19 extends at an acute angle 40 with respect to the axis of the standard 11.

The screw 21 is attached to the jaw 20 and is slidably mounted in a boss on the portion 19.

The member 13 likewise has a portion 27 which extends acutely from the axis of the standard 11, and adjacent this portion 27 is a gripping jaw 28 that is normally urged slightly away from the standard 11 by a spring-urged screw 29 that is similar to screw 21 and which is slidably mounted in a boss 55 on portion 27.

Attached to jaw 28 is a screw 30 upon which is a spring 32. The spring 32 is arranged within a sleeve 23 which embraces the heads of the screws 24 and 30. The sleeve 60 65 23 has a flange 26 and a flanged member 25 is slidably mounted on screw 24.

Attached to the sleeve 23 is a screw 31 upon which is a spring 33. The spring 33 is arranged within a sleeve 23 which embraces the heads of the screws 24 and 30. The sleeve 70 75 23 has a flange 26 and a flanged member 25 is slidably mounted on screw 24.

The springs 31 and 32 urge the jaws 20 and 28 into gripping engagement with the standard 11 (upwardly as seen in Figs. 2 and 4) 76 and into wedging engagement with the portions 19 and 27. Pivotaly mounted on member 12 is a latching lever 22 which has a pair of fingers 33 that are engageable with the flange 26 of sleeve 23. A second lever 34 is pivotally mounted on member 12 and has a cam portion 35 that is engageable with the lever 22 whereby to move the lever 22 into latched position (Fig. 2) and unlatched position (Fig. 4). When moved into latched position the fingers 33 on the lever 22 engage the flange 26 and slide the sleeve 23 upwardly, thereby tensioning spring 32, which tends to draw the jaw 28 upwardly into gripping engagement with standard 11. Upward movement of the sleeve 23 by means of the latching lever fingers 22, likewise compresses the spring 31 because of the engagement of flange 26 with the flange 25 as the sleeve 23 is moved upwardly, and the jaw 20 is therefore likewise urged upwardly into gripping engagement with standard 11. 80 85 90

The parts being in latched or lifting position, as in Fig. 2, and the load bearing, relative to standard 11, on member 12, downward movement of operating lever 14 exerts an upward pull on member 13 and jaw 28 by reason of the eccentric throw 16 and link 17. As the member 13 is moved upwardly the weight of the load, relative to standard 11, is shift- 100

ed to member 13 whereupon the portion 27 forces the jaw 28 into holding engagement with the standard 11. The operating lever 14 being then moved upwardly, the member 12 is raised, by means of the eccentric crank throw 16 and link 17 while the member 13 remains relatively stationary. As the member 12 is thus moved upwardly, by upward movement of operating lever 14, crank throw 16 and link 17, the bearing reaction of the load, relative to standard 11, is shifted from member 13 to member 12 and the weight of the load, acting through the portion 19 of member 12, forces the jaw 20 into holding engagement with the standard 11 while at the same time, since the weight of the load is shifted from member 13 to member 12, the jaw 28 is released from holding engagement with standard 11, permitting the member 13 to be moved upwardly when the operating lever 14 is again moved downwardly. Upon the next downward movement of operating lever 14 the weight or bearing reaction of the load, relative to standard 11, is again transferred from member 12 to member 13 which, acting through portion 27, forces the jaw 28 into holding engagement with standard 11. During each of these operations of shifting the load, relative to standard 11, from member 13 to member 12 and vice versa, the compressed springs 31 and 32 keep the jaws 20 and 28 in grabbing contact with the standard 11.

The parts are arranged in unlatched position in Fig. 4 wherein it will be seen that the lever 34 has manipulated the lever 22, counterclockwise from the position of lever 22 in Fig. 2, thereby relieving tension on spring 32 which has forced the sleeve 23 downwardly into engagement with jaw 28 while at the same time the tension on spring 31 is relieved. The jaws 20 and 28 are, therefore, now urged by the adjustable springs 35 and 36, on screws 21 and 29, slightly away from the standard 11 so that the members 12 and 13 may be lowered on the standard 11 by reciprocating the operating lever 14 alternately up and down. To facilitate lowering of the members 12 and 13 on standard 11, the springs 35 and 36 are kept tensioned sufficiently to draw the jaws 20 and 28 slightly away from the standard 11 when the springs 31 and 32 are relaxed, as in Fig. 4; but the normal tension of these springs 35 and 36 is insufficient to pull the jaws 20 and 28 away from the standard 11 when the parts are in latched position and the springs 31 and 32 are tensioned as in Fig. 2.

A clamping jaw 37 is removably mounted on the standard 11 to cooperate with member 12 when the jack is used as a pulling device or for other purposes readily apparent to those skilled in the art.

While I have illustrated and described the preferred form of construction for carry-

ing my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A jack comprising a standard, a pair of members movable axially along the standard and each including a portion extending at an acute angle with respect to the axis of the standard, a gripping jaw carried by each of said members and each of said jaws including a portion adapted for wedging engagement with one of said first-named portions, a crank including an eccentric throw rotatably mounted in one of said members, an operating lever attached to the crank, a link connecting the throw and the other of said members, and latch-controlled means urging the gripping jaws into engagement with the standard and said jaw portions into wedging engagement with said first-named portions.

2. A jack comprising a standard, a pair of spaced members movable axially along the standard, and each including a portion extending acutely with respect to the axis of the standard, a gripping jaw carried by each of said members, each of said jaws including a portion adapted for wedging engagement with one of the first-named portions, a crank rotatably mounted in one of said members and including an eccentric throw, a link connecting the throw and the second-named member, resilient means urging the jaws into gripping engagement with the standard and said portions into wedging engagement, latch mechanism in latched position compressing said means, and resilient means urging said jaws out of gripping engagement with the standard and said portions out of wedging engagement, when said latch mechanism is in unlatched position.

3. A jack comprising a standard, a pair of members movable axially along the standard and each including a portion extending at an acute angle with respect to the axis of the standard, a gripping jaw carried by each of said members and each of said jaws including a portion adapted for wedging engagement with one of said first-named portions, a crank including an eccentric throw rotatably mounted in one of said members, an operating lever attached to the crank, a link connecting the throw and the other of said members, latch-controlled means urging the gripping jaws into engagement with the standard and said jaw portions into wedging engagement with said first-named portions.

portions, and means urging the jaws out of gripping engagement with the standard and said portions out of wedging engagement when the latch-controlled means are in ineffective position.

4. A jack comprising a standard, a pair of members movable axially along the standard and each including a portion extending at an acute angle with respect to the axis of the standard, a gripping jaw carried by each of said members and each of said jaws including a portion adapted for wedging engagement with one of said first-named portions, a crank including an eccentric throw rotatably mounted in one of said members, an operating lever attached to the crank, a link connecting the throw and the other of said members, resilient means urging the gripping jaws into engagement with the standard and said portions into wedging engagement, latch mechanism for compressing said resilient means, and other resilient means urging said jaws out of gripping engagement and said portions out of wedging engagement when said latch mechanism is in ineffective position.

In testimony whereof I affix my signature.
EMIL J. SEEBER.
